DISTILLATION OF OIL

Frank L. Maker, Berkeley, Calif., assignor to
Standard Oil Company of California, San Francisco, Calif., a corporation of Delaware

Application May 24, 1935, Serial No. 23,282

5 Claims. (Cl. 196—108)

This invention relates to the distillation of oil by a fractionation process and particularly to a method and means for adding heat to the liquid in the lower part of a fractionating column and 5 withdrawing stripped residuum therefrom.

In the practice of fractionating or stripping lighter components from a liquid mixture, it is usually necessary to add heat to the lower portion of a fractionating column, which heat is 10 carried upward through the column by means of vapors. This is commonly done by heating the reflux liquid in the bottom of the column, that has flowed from the fractionating plates above, and vaporizing a portion or all of it, which vapors, 15 together with any other fluid, such as steam, that may be added to promote distillation or reduce maximum temperatures or for other purposes, pass upward through the column acting as a vehicle for the heat. In continuous processes 20 a portion of the liquid in the lower part of the column is withdrawn continuously from a column as stripped product, or bottom, or residuum.

The reflux liquid overflowing from the bottom fractionating plate contains more light fractions 25 than is desired in the residuum or bottoms passing out of the column. It is therefore desirable to insure that all of the liquid coming from the bottom plates passes at least once over the heating surface before it has opportunity to pass out 30 through the bottom or residuum draw-off connection.

In some cases it has been the practice, in order 35 to achieve this object, to pass over the heating surface only the liquid overflowing from the bottom fractionating plate. This method has the objection that if there is any fluctuation of the rate of overflow from the bottom plate, there will be a change in the quantity of liquid passed over the heating surface, and if the heat input is constant or nearly so, as is usual, there will be a corresponding inverse fluctuation of the temperature. The temperature of the liquid may rise to a higher point than is desirable or the heating surface may become overheated due to insufficient 40 liquid circulating over it to keep it cool. To avoid this, it is desirable to circulate liquid over the heating surface at a greater rate than the rate of overflow from the bottom fractionating plate, so that a portion of the circulating liquid is continuously recirculated.

With this arrangement, it is sometimes the practice to discharge the liquid overflowing from the bottom fractionating plate into the entrance 45 pipe to the circulating and heating system, as in my copending application Serial No. 607,383 filed

April 25, 1932, which matured into Patent No. 2,031,610 on February 25, 1936, so that the overflow or reflux liquid will be certain to pass at least once over the heating surface. This, however, has a disadvantage that the hotter liquid being 5 recirculated tends to cause vaporization in the heater system of the lighter components of the reflux liquid that has overflowed from the bottom fractionating plate, which liquid is always richer in the lower boiling components than is the 10 residuum, and which is also at a lower temperature than the latter. This vaporization causes difficulty in pumping the liquid being circulated past the heating surface, and may become sufficiently aggravated, especially when the system 15 is being operated at pressure less than atmospheric, to make the pump inoperative by so-called vapor-locking.

My invention comprehends a system of baffle means in the reservoir at the bottom of such a 20 column and a mode of operation thereof that will insure proper and efficient operation, so that all entering reflux will be adequately heated, exposed to an extended surface to permit escape of light fractions and positively directed through the heating 25 means.

It is an object of this invention to insure that all of the reflux liquid overflowing from the bottom fractionating plate passes over the heating surface at least once before it is withdrawn as 30 residuum or bottoms.

It is also an object of this invention to provide a circulation rate over the heating surface that is greater than the rate of overflow of liquid from the bottom fractionating plate.

A further object is to secure a mixing of the liquid overflowing from the bottom plate with the excess liquid that has just returned from being passed over the heating surface, whereby the lighter ends in the overflow liquid are evaporated 40 and removed from the liquid before it enters the circulating stream, so that vaporization does not take place in the circulating system.

Another object is to provide a definitely maintained direction of flow of reflux and residuum 45 in the bottom of a fractionating column to insure adequate stripping thereof.

Another object is to provide a means and mode of operation that will reduce the vaporization and increase the capacity of a circulating pump 50 and tubular heater in an installation of the character described.

Another object is to provide a method and means for operating a fractionating column that will prevent vapors from getting into and mov- 55

ing upwardly in a reflux conduit or downspout, thus insuring that the liquid downflow will not be interrupted or reversed and the column caused to "head".

- 5 These and other objects and advantages will be more fully apparent from the following description and from the accompanying drawing, which forms a part of this specification, and illustrates a preferred embodiment of this invention.
- 10 The drawing is a diagrammatic and part sectional view of a fractionating column and a tubular heater therefor, the latter adapted to add heat to the reservoir at the bottom of the column, with a preferred arrangement of baffles in said reservoir to direct the flow therein.

15 Referring to the drawing, the numeral 10 designates generally the fractionating column, which may be of the conventional type with a shell 11, liquid-vapor contact plates 12, feed inlet 13, and vapor outlet 14. A reflux flow conduit 15 is provided from the bottom plate, said conduit extending downwardly into the reservoir 16 in the bottom of the column.

20 An overflow weir or baffle 17 is provided as a means for withdrawing circulating liquid from reservoir 16 and controls the flow of said liquid to the circulation outlet conduit 18. Pump 19 in conduit 18 urges the liquid through a conventional tubular heater 20 and back into reservoir 16 through conduit 21.

25 Reservoir 16 is divided by a partition or partial baffle 22 into a first chamber 23 and a second chamber 24, with a communicating passage 25 so that liquid may flow from the bottom of chamber 30 23 into chamber 24 for a purpose to be described below.

35 The heated liquid returns from heater 20 through conduit 21 to reservoir 16 over a spreader element 26 (optional) into said first chamber 23 and mixes with the residuum therein. Liquid from chamber 23 flows through passage 25 into second chamber 24, where it mixes with and imparts heat to the reflux liquid from conduit 15, which latter extends into said second chamber 40 24, as shown. The tar or residuum outlet conduit 27 from reservoir 16 extends into first chamber 23 and preferably to a point higher than the outlet of reflux conduit 15, so that a liquid seal will at all times be maintained for said latter conduit, thus preventing vapors in the reservoir 16 from 45 entering the same, and interfering with the downward flow of liquid therethrough. The sealing relation just outlined for reflux conduit 15 is further maintained by the overflow weir 17 which is preferably located at a point higher than the lower end of conduit 15, as will be apparent from the drawing. If such should occur, the fractionating column would tend to "head" and its operation 50 would be upset.

55 In operation, the rate of circulation through conduit 18, pump 19, heater 20 and conduit 21 is maintained at a rate higher than the rate of reflux flow from plates 12 through reflux conduit 15 into the second chamber 24 of reservoir 16. Thus the direction of flow of liquid in the various chambers of reservoir 16 is always in the direction indicated by the arrows, or from first chamber 23 through passage 25 into second chamber 24. This insures that no reflux from conduit 15 will 60 pass backwardly from chamber 24 into chamber 23 and go unstripped out of the tar or residuum draw 27.

65 As stated above the reflux from conduit 15 entering chamber 24 is at a lower temperature

than the liquid in reservoir 16 generally, particularly that flowing from chamber 23 to chamber 24, and also contains lighter fractions. As the reflux enters chamber 24 it is mixed with the hotter liquid therein and, before passing into the 5 circulating system it flows over weir 17 thus being adequately exposed to the vapor space in the reservoir 16, so that the light fractions may be boiled off. The partially stripped reflux, mixed with the residuum liquid from chamber 23 then 10 passes through the tubular heater 20, wherein more heat is added. Any vaporizable fractions remaining are released as the heated liquid from conduit 21 spreads over spreader member 26 or is exposed at the top of chamber 23. As also 15 stated above, residuum may be continuously withdrawn through tar draw 27.

20 A further advantage of the initial and partial removal of the lighter fractions from the reflux by its contact in chamber 24 with hot recirculated residuum from chamber 23, and before it passes over weir 17 into the circulating and heating system, is the decreased vaporization that takes place in the circulating pump 19 and tubular heater 20, thus increasing the capacity and 25 decreasing the carbon deposition in the latter.

30 It will readily be recognized that it is not necessary for the reservoir 16 and the fractionating column 10 to be in the same shell, as has been shown for convenience in this example, so long as reflux liquid can be passed from said column into said reservoir and vapor from said reservoir can be returned to said column.

35 Although a specific construction embodying this invention has been described and illustrated it is to be understood that the invention is not limited to that specific device or mode of operation described for it, and all such modifications and claims as come within the scope of the appended claims are embraced thereby. 40

I claim:

1. An apparatus for distilling oil comprising a fractionating column, a separate oil heater, a reservoir for liquid, means in said reservoir dividing the same into a first chamber and a second chamber, a substantially unrestricted passage for liquid from said first chamber to said second chamber, means for conducting reflux from said fractionating column into said second chamber, means for withdrawing liquid from said second chamber at a point higher than the outlet of said last named means, passing said liquid through said heater and returning said liquid to said first chamber, and means for passing vapors from both chambers of said reservoir directly 55 into said fractionating column.

2. An apparatus according to claim 1 in which said reservoir is positioned in the lower part of said fractionating column and said reflux conducting means comprises a conduit for keeping 60 said reflux out of contact with the vapors from said reservoir.

3. An apparatus for distilling oil, comprising a fractionating column, liquid-vapor contact plates in said column, a tubular oil heater, a reservoir in the bottom of said column, flow restricting means in said reservoir for dividing the same into a first chamber and a second chamber, conduit means for conducting reflux from the lowest plate in said column into said second 65 chamber out of contact with the vapors from said reservoir, a circulating liquid conduit leading out of said second chamber to said heater from a point in said chamber higher than the outlet of said reflux conduit means to form a 70 75

seal therefor, a pump in said last named conduit, a circulating fluid conduit from said heater to said first chamber, and a residuum outlet from said first chamber.

5. An apparatus for distilling oil, comprising a fractionating column, liquid-vapor contact plates in said column, a tubular oil heater, a reservoir in the bottom of said column, a baffle in said reservoir for dividing said reservoir into a first 10 chamber and a second chamber, a liquid passage in the lower part of said baffle, a conduit for reflux from the lowest plate in said column, said conduit terminating in the lower part of said second chamber and adapted to keep said reflux 15 out of contact with the vapors from said reservoir, a level control weir in said second chamber, a conduit leading from behind said weir to said heater, a pump in said conduit, a return conduit from said heater to said first chamber, and a

residuum outlet from said first chamber above the lower end of said reflux conduit, said outlet and said weir cooperating to form a liquid seal for said reflux conduit.

5. An apparatus for distilling oil comprising a fractionating column, a reservoir divided into a first chamber and a second chamber, means for passing reflux from said column into said second chamber without contacting said reflux with vapors from said reservoir, means for withdrawing 10 liquid from said second chamber at a point higher than the outlet of said last named means to form a seal for the same, means for heating said liquid, means for delivering it to said first chamber, and means for passing a portion of said heated 15 liquid from said first chamber to said second chamber without substantial pressure drop.
